UNITED STATES PATENT OFFICE

ARTHUR VON FRANKENBERG, OF NEW YORK, N. Y.

DESIGN FOR A STAND FOR SMOKER'S AND SIMILAR ARTICLES

Application filed May 9, 1931. Serial No. 39,793. Term of patent 3½ years.

To all whom it may concern:

Be it known that I, ARTHUR VON FRANKENBERG, a citizen of the United States of America, and a resident of New York city, in the county and State of New York, have invented a new, original, and ornamental Design for Stand for Smoker's and Similar Articles, of which the following is a specification, reference being had to the accompanying drawing, forming part hereof.

The figure is a pictorial view of my new design supporting an ash tray, and is also adaptable to serve as a stand for a clock or a dinner gong and similar articles.

I claim:

The ornamental design for a stand for smoker's and similar articles, as shown.

ARTHUR VON FRANKENBERG.
